[57] CLAIM

The ornamental design for a container for treating animals, as shown and described.

DESCRIPTION

FIG. 1 is a perspective view of my container for treating animals;

FIG. 2 is a left, side, elevational view thereof, with the right, side, elevational view being substantially a mirror image thereof;

FIG. 3 is a top, plan view thereof;

FIG. 4 is a bottom, plan view thereof;

FIG. 5 is a back, elevational view thereof;

FIG. 6 is a front, elevational view thereof;

FIG. 7 is a perspective view of an alternative embodiment of my inventive design as shown in FIG. 1;

FIG. 8 is a left, side, elevational view of the alternative design with the right, side, elevational view being substantially a mirror image thereof;

FIG. 9 is a top, plan view of the alternative design;

FIG. 10 is a bottom view of the alternative design;

FIG. 11 is a front, elevational view of the alternative design; and,

FIG. 12 is a back, elevational view of the alternative design.

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.
